UNITED STATES PATENT OFFICE.

HARRIS HAUSMAN, OF BROOKLYN, NEW YORK.

DESIGN FOR TEXTILE FABRIC.

Application filed February 8, 1924. Serial No. 8,579. Term of patent 3½ years.

To all whom it may concern:

Be it known that I, HARRIS HAUSMAN, a citizen of the United States, residing at 1126 East 22nd Street, Brooklyn, in the county of Kings, State of New York, have invented a new, original, and ornamental Design for Textile Fabric, of which the following is a specification, reference being had to the accompanying drawing, forming part thereof.

In the drawing:

The figure is a plan view of a section of the textile fabric.

I claim—

The ornamental design for textile fabric, as shown.

HARRIS HAUSMAN.
